VIOLIN BOW

Original Filed Aug. 4, 1922

2 Sheets-Sheet 2

UNITED STATES PATENT OFFICE.

CHARLES B. GRAY, OF PHILADELPHIA, PENNSYLVANIA.

VIOLIN BOW.

Application filed August 4, 1922, Serial No. 579,696. Renewed January 10, 1928.

My improvement relates particularly to the manner of attaching the hair to the frog and nut of violin bows.

The object of the invention is to so join the flat bunch or strip of hair to the frog and to the nut as to permit the bunch of hair to rest flatwise on the string regardless of the radial position of the bow, in order that, when so desired, the entire width of the bunch of hair will make contact with the string during the entire stroke of the bow. But it is also intended that there shall be sufficient resistance to the turning of the bunch of hair to permit moving the bow across the string with only the edge of the bunch of hair making contact with the string, as is desirable when the tone is to be weak.

The improvement includes a form of terminal structure for engaging the ends of the hair and includes also means for engaging such terminal structure to the frog and to the nut of the bow, in such manner as to permit rocking of the terminal structures on an axial line which is parallel to the bunch of hair.

In the accompanying drawings:

Fig. 1 is a perspective of a violin bow embodying my improvement, the bow being inverted and the middle part thereof being broken away;

Fig. 2 shows a part of the frog and the adjacent end of the ribbon of hair and the terminal for securing the hair, these parts being inverted;

Fig. 3 is a section on the line, 3-3, of Fig. 2;

Fig. 4 is a section on the line, 4-4, of Fig. 2, looking toward the right.

Fig. 5 is a section on the line, 5-5, of Fig. 3, looking toward the right;

Figs. 6 and 7 illustrate another form of means for connecting the terminal structure with the frog, Fig. 7 being a section on the line, 7-7, of Fig. 6;

Figs. 8 and 9 illustrate another form of means for connecting the terminal structure with the frog, Fig. 9 being a section on the line, 9-9, of Fig. 8.

Figs. 10, 11 and 12 illustrate another form of terminal structure, Fig. 11 being an upright section on the line, 11-11, of Fig. 10, looking toward the right, and Fig. 12 being

an upright section on the line, 12-12, of Fig. 10, looking toward the right;

Figs. 13, 14 and 15 illustrate another form of terminal structure, Fig. 14 being an upright section on the line, 14-14, of Fig. 13, looking toward the left, and Fig. 15 being an upright section on the line, 15-15, of Fig. 13, looking toward the left;

Figs. 16 and 17 illustrate the form of terminal structure shown by Figs. 13, 14 and 15, with the addition of cloth applied around the end of the hair bunch;

Figs. 18 and 19 illustrate a terminal structure similar to that shown by Figs. 2, 3, 4 and 5, and metal members for joining the terminal structure to the adjacent abutment.

Referring first to Figs. 1, 2, 3, 4 and 5 of said drawings, A is the bow stick, B is the nut, and C is the frog slideable on the bow stick by means of the tension screw, D, through any well known connection between the screw and the frog. E is the bunch of hair which is stretched between the nut and the frog. The frog and the nut each constitute an abutment for the suspension of the bunch or strip of hair. To each end of the bunch, E, is attached a terminal structure, F. Said structure comprises a member, F¹, and a member, F². Said members together form a clamp for engaging the bunch of hair. The member, F², has a horizontal part over which extends the member, F¹, the body of the member, F¹, being parallel to the body of the member, F². But the member, F¹, is long enough to allow folding over the ends of the member, F². The hairs of the bunch, E, extend across the upper face of the member, F¹, and then downward and in the reverse direction between the members, F¹ and F². In folding the ends of the member, F¹, said ends are made to bear against the lower face of the member, F²,

with sufficient force to clamp the hair between the lower face of the member, F¹, and the upper face of the member, F². Before this engagement is made, if so desired, an adhesive may be applied to the hair or to the opposing faces of the members, F¹ and F², for causing adhesion of the hairs to each other and to the members, F¹ and F². To provide added strength, the ends of the member, F¹, may be soldered to the member, F², by the use of a solder which does not

injuriously heat the hair. The ends of the hair are preferably made to project through the space between the members, F^1 and F^2 , and the ends then seared by the application 5 of a hot tool, such searing resulting in the thickening of the ends of the hair and such thickening acting the same as would a knot for preventing the slipping of the hair between the members, F^1 and F^2 . The edge 10 of the member, F^2 , which is nearer the other terminal is turned downward to form a flange, F^3 , which bears against the adjacent edge of the member, F^1 —the ends of the member, F^1 , which are turned under the 15 member, F^2 . The opposite edge of the member, F^2 , is extended horizontally beyond the adjacent edge of the member, F^1 , and then turned upward to form a flange, F^4 . In said flange are two horizontal eyes, F^5 , 20 which are substantially at the level of the bunch of hair, E , and at opposite sides and equi-distant from the middle line of the bunch of hair.

An endless cord, G , extends through said 25 two eyes and over the lower face of the frog and around a screw, G^1 , and between a washer, G^2 , and the frog, the washer surrounding the screw and the screw extending into the frog. The cord, G , may be composed of any pliable or flexible material. A piece of closely woven fish line will 30 answer. The piece being cut of suitable length and its ends tied together to make the cord continuous.

35 When the tension screw, D , is turned to slide the frog for putting the hair under tension, the bow stick bends to some extent, and thereby the frog is tilted relative to the axial line of the hair bunch. When 40 that occurs, the cord, G , bends at the place of its contact with the frog nearest the adjacent terminal structure.

It is to be observed that the cord, G , constitutes a tension member extending from 45 the terminal structure to the screw, G^1 , and said tension member is easily bendable.

At the other end of the bow, a second terminal is formed like the terminal already described, and the connection between the 50 second terminal and the nut is made by a cord, G , screw, G^1 , a washer, G^2 , the screw and the washer being seated on the lower face of the nut.

When the frog is drawn by the tension 55 screw, D , the cord, G , which is on the frog is drawn in the same direction, by the screw, G^1 . By this means the adjacent terminal structure is drawn in the same direction, whereby the bunch of hair, E , and the second 60 tension structure and the cord on the nut are put under tension. The degree of such tension is determined by the person turning the tension screw, D .

When such tension has been produced, the 65 terminal structures will stand parallel to

the lower faces of the frog and the nut, this being effected by the two parts of each of the cords, G . But each terminal structure is free to be tilted approximately on the axial line of said structures and the bunch of hair. 70 Either part of the cord, G , may move away from the adjacent face of the frog or the nut, the rotation of the terminal structure being on the other part of the cord, G . The ease with which the terminal structures may 75 be thus tilted depends upon the distance between parts of the cord, which depends upon the distance between the eyes, F^5 . If those eyes are near each other, such tilting is easier than when said eyes are separated 80 relatively far from each other. The ease with which such tilting may be produced is also dependent to some extent upon the distance between the terminal structure and the screw, G^1 .

During ordinary use of the bow on the violin, the pressure of the bow on the strings is to be sufficient to cause the tilting of the terminal structures so as to keep the entire width of the bunch or strip of hair flat upon 90 the string during the entire stroke, whereby the tone is kept of uniform strength throughout the entire stroke. But if soft tones are desired, the bow is to be turned with light pressure so as to cause the edge 95 of the bunch of hair to bear upon the string, the pressure applied to the bow being insufficient to over-come the resistance which the terminal structures offer to tilting.

In Figs. 6 and 7 the ends of the cord are 100 not tied to each other. They are clamped between said washer and the adjacent face of the frog or the nut. This form permits easy adjustment of the space between the screw, G^1 , and the flange, F^4 , of the terminal 105 structure, such adjustment being made by retracting the screw, G^1 , until the washer releases the cord sufficiently to permit drawing the cord through the desired distance in the required direction.

In Figs. 8 and 9, the face of the frog or nut is provided with a recess, G^4 , sufficiently deep to receive the washer and cord, and the edges of the washer are provided with notches, G^3 , to receive the cord, the parts of 115 the cord covered by the washer being pressed into the recess. By this means stronger engagement of the cord is produced than is the case when the washer is merely seated on the face of the frog or nut.

In the form shown by Figs. 10, 11 and 12, the terminal structure is formed of a single piece of sheet metal, F^6 , which resembles the member, F^1 , of Figs. 2, 3 and 4, the member, F^6 , being long enough to be bent around the 125 hair bunch, as shown by Fig. 12. On said member is a horizontal extension, F^7 , on which is a flange, F^8 , corresponding to the flange, F^4 , of Figs. 2 and 3. Said flange has two eyes, F^9 , corresponding to the eyes, F^5 , 130

in the flange, F^4 , of Figs. 2 and 3. The eyes, F^9 , receive the cord, G , which is secured by the screw, G^1 , and the washer, G^2 . In this form of the terminal structure, the hair 5 bunch is not folded as in Figs. 2 and 3.

In Figs. 13, 14 and 15, the terminal structure consists of a single piece folded to engage the end of the hair bunch and to form a flange, F^8 , having eyes, F^9 , to receive the 10 cord, G . The edge which is opposite the flange, F^8 , is folded to clamp the end of the hair bunch which is correspondingly folded in the reverse direction. In the form shown by Figs. 16 and 17, the construction is the 15 same as the last preceding form, excepting that a band of cloth, F^{10} , is placed around the end of the hair bunch and secured there-to by adhesive before the hair bunch is engaged by the terminal structure.

In Figs. 18 and 19, a coupling between the terminal structure and the abutment is formed by applying to the abutment a metal plate, I , which is secured by a screw, J^2 , extending through the plate. This plate projects beyond the abutment toward the adjacent terminal structure and is shaped to form an apertured half ball socket, I^2 . A stem, I^3 , is fixed on the flange, F^4 , of the terminal structure and extends into the socket, I^2 , and there supports a half ball, I^4 , which is seated in said socket. In the aperture in the plate, I , space is left around the stem, I^3 , to permit lateral movement of said stem in any direction. Thus provision 30 is made for permitting the tilting of the adjacent terminal structure and also to permit tilting of the frog relative to the length of the hair bunch when the tension screw is turned. With the terminal structure and 35 the abutment, I associate means for yieldingly holding the hair bunch parallel to the lower faces of the abutments. A wire spring, J , resembling a wire hair pin with an inward fold, J^1 , at the closed end is held 40 to the abutment by means of a screw, J^2 . The ends of the wire, J , rest upon the edge of the flange, F^4 . The wire is long enough and thin enough to adapt it to bend under small strains, in order that the terminal 45 structure may readily turn when the hair bunch is pressed upon a violin spring and yet return to normal position when such pressure has been released, and in order that, for the making of a light tone, the bow may 50 be drawn with one edge of the hair bunch across the violin string.

It is to be noted that the terminal structures are to be made compact and that it is preferable to make them light. For this 55 purpose, aluminum or an alloy of aluminum may be used.

I claim as my invention,

1. In a violin bow, the combination with the bow stick and two abutments adjustable 60 relative to each other, of a bunch of parallel

hair having one end in operative relation with one of said abutments, a terminal structure secured to the other end of the bunch of hair and spaced from the adjacent abutment, and a twistable tension member joined to 70 said terminal structure and the adjacent abutment, substantially as described.

2. In a violin bow, the combination with the bow stick and two abutments adjustable 75 relative to each other, of a bunch of parallel hair having one end in operative relation with one of said abutments, a terminal structure secured to the other end of the bunch of hair and spaced from the adjacent abutment, and a cord joined to said terminal structure and the adjacent abutment, substantially 80 as described.

3. In a violin bow, the combination with the bow stick and two abutments adjustable 85 relative to each other, of a bunch of parallel hair having one end in operative relation with one of said abutments, a terminal structure secured to the other end of the bunch of hair and spaced from the adjacent abutment, a screw on the adjacent abutment, and a twistable tension member joined to said terminal structure and in operative relation with said screw, substantially as described.

4. In a violin bow, the combination with a bow stick and two abutments adjustable 90 relative to each other, of a bunch of parallel hair having one end in operative relation with one of said abutments, a terminal structure secured to the other end of the bunch of hair and spaced from the adjacent abutment, a screw on the adjacent abutment, and a cord joined to said terminal structure and in operative relation with said screw, substantially as described.

5. In a violin bow, the combination with the bow stick and two abutments adjustable 95 relative to each other, of a bunch of parallel hair having one end in operative relation with one of said abutments, a terminal structure secured to the other end of the bunch of hair and spaced from the adjacent abutment, and a twistable tension member joined to said terminal structure, and a screw and a washer in operative relation with said tension member and seated on said abutment, substantially as described.

6. In a violin bow, the combination with the bow stick and two abutments adjustable 100 relative to each other, of a bunch of parallel hair having one end in operative relation with one of said abutments, a terminal structure spaced from the adjacent abutment and applied to the other end of the hair bunch and including a folded metal plate, and twistable means joining the terminal structure to the adjacent abutment, substantially 105 as described.

7. In a violin bow, the combination with the bow stick and two abutments adjustable 110 relative to each other, of a bunch of parallel

- hair having one end in operative relation with one of said abutments, a terminal structure spaced from the adjacent abutment and applied to the other end of the hair bunch 5 and including a transverse metal member folded upon itself transversely to the length of the bow, and twistable means joining the terminal structure to the adjacent abutment, substantially as described.
10. 8. In a violin bow, the combination with the bow stick and two abutments adjustable relative to each other, of a bunch of parallel hair having one end in operative relation with one of said abutments and having its 15 opposite end folded, a terminal structure spaced from the adjacent abutment and engaging the folded end of the hair bunch, and twistable means joining the terminal structure to the adjacent abutment, substantially as described.
17. 9. In a violin bow, the combination of a bow stick and two abutments adjustable relative to each other, of a bunch of parallel hair having one end in operative relation 25 with one of said abutments, a terminal structure spaced from the adjacent abutment and applied to the other end of the hair bunch and twistable tension means in operative relation with the adjacent abutment and 30 engaging the terminal structure at diverse points substantially as described.
18. 10. In a violin bow, the combination with a bow stick and two abutments adjustable relative to each other, of a bunch of parallel hair having one end in operative relation 35 with one or said abutments, a terminal structure spaced from the adjacent abutment and secured to the other end of the bunch of hair and having two eyes, and twistable tension means joined to the adjacent abutment and engaged in said eyes, substantially as described.
19. 11. In a violin bow, the combination with a bow stick and two abutments adjustable 45 relative to each other, of a bunch of parallel hair having one end in operative relation with one of said abutments, a terminal structure spaced from the adjacent abutment and secured to the other end of the bunch of hair, a twistable tension member engaging the terminal structure, and means on the adjacent abutment engaging the ends of the tension member, substantially as described.
20. 12. In a violin bow, the combination with a bow stick and two abutments adjustable 55 relative to each other, of a bunch of parallel hair having one end in operative relation with one of said abutments, a terminal structure spaced from the adjacent abutment and secured to the other end of the bunch of hair, a twistable tension member engaging the terminal structure, and a screw and 60 washer located on the adjacent abutment and engaging the ends of the tension members, substantially as described.
21. 13. In a violin bow, the combination with a bow stick and two abutments adjustable relative to each other and the second of which has a recess, of a bunch of parallel hair having one end in operative relation with the first 70 of said abutments, a terminal structure spaced from the adjacent abutment and secured to the other end of the bunch of hair, a screw and a washer in the recess of the adjacent abutment, and a twistable tension member joined to said terminal structure and extending into said recess and beneath said washer substantially as described.
22. 14. In a violin bow, the combination with the bow stick and two abutments adjustable relative to each other, of a bunch of parallel hair having one end in operative relation 75 with one of said abutments, a terminal structure spaced from the adjacent abutment and applied to the other end of the hair bunch, and a duplex twistable tension means secured to the terminal structure and to the horizontal face of the adjacent abutment and resting upon said face at opposite sides of the axis of the bunch of hair, substantially as described.
23. 15. In a violin bow, the combination with the bow stick and the abutments, of a bunch of parallel hair and means attaching the ends 85 of the bunch of hair to the abutments and engaging the abutments at each side of a line which is approximately coincident with the middle longitudinal line of the bunch of hair, substantially as described.
24. 16. The combination of a bunch of parallel hair, a terminal structure, a twistable tension member extending to each side of the axis of the bunch of hair and adapted to extend over and rest on and be secured to the face of a violin bow abutment, substantially as described.
25. 17. The combination of a bunch of parallel hair, a terminal structure, and a duplex twistable tension member extending to each side of the axis of the bunch of hair and adapted to extend over and rest on and be secured to the face of a violin bow abutment, substantially as described.
26. 18. The combination of a violin bow abutment, a bunch of parallel hair, a bendable terminal structure spaced from the adjacent abutment, and a twistable connecting member for joining the terminal structure rotatably to said abutment, substantially as described.

In testimony whereof I have signed my name, this 3rd day of August, in the year one thousand nine hundred and twenty-two.

CHARLES B. GRAY,
